UNITED STATES PATENT OFFICE.

CHAUNCEY HOLT, OF JERSEY CITY, NEW JERSEY.

IMPROVEMENT IN CHILDREN'S CARRIAGES.

Specification forming part of Letters Patent No. 120,645, dated November 7, 1871.

To all whom it may concern:

Be it known that I, CHAUNCEY HOLT, of Jersey City, in the county of Hudson and State of New Jersey, have invented a certain Improvement in Children's Carriages; and I do hereby declare that the following is a full, clear, and exact description thereof, which will enable others skilled in the art to make and use the same, reference being had to the accompanying drawing forming part of this specification, in which—

Figure 1 represents a longitudinal vertical section of my improved children's carriage, the line *c c*, Fig. 2, indicating the plane of section. Fig. 2 is a vertical transverse section of the same taken on the plane of the line *k k*, Fig. 1.

Similar letters of reference indicate corresponding parts.

The object of this invention is to provide a children's perambulator or carriage with a drawer, wherein to keep articles of food and other appliances that may be necessary or convenient for use of small children. The invention consists in the application of a drawer to a children's carriage, when arranged in the lower part of the carriage-body in guides, and so that it can be ope-

rated by being drawn backward, forward, or to the side.

A in the drawing represents the carriage-body supported on three or more wheels, *B B*, and made of suitable form or size. *C* is a sliding drawer, applied to the lower part of the carriage-body so that it can be opened by being drawn backward, it being thus within convenient reach of the person pushing the carriage. For the support of this drawer side rails *a a* are affixed to the lower part of the carriage-body; between them the drawer slides and has its support. In some kinds of children's carriages the drawer may be so arranged under the carriage-body as to open by being drawn forward or to the side.

Having thus described my invention, I claim as new and desire to secure by Letters Patent—

A children's carriage having a sliding-drawer under the carriage-body, substantially as set forth.

The above specification of my invention signed by me this 27th day of September, 1871.
